(57) **CLAIM**

The ornamental design for a mobile phone, as shown and described.

DESCRIPTION

FIG. 1 is a front perspective view of a mobile phone showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines that are immediately adjacent to the areas included in the claim, and define unshaded regions, represent the bounds of the claim. All other broken lines, including the broken lines within broken line boundaries, the display rectangle and the tiny circles, which occur beneath the front surface, and the circular camera features at the rear, show environment. The broken lines form no part of the claimed design.
